LIQUID DISPENSING APPARATUS FOR DISPENSING MEASURED AMOUNTS OF BEVERAGES

Hartwell De Mille, New York, N. Y.

Application June 22, 1948, Serial No. 34,401

5 Claims. (Cl. 225—21)

1

This invention is an improved liquid dispensing apparatus; particularly a coin-controlled apparatus for delivering a measured quantity of a flavored non-alcoholic beverage, or alcoholic liquors too if desired.

An important object of my invention is to simplify the design of apparatus of this kind, to provide a complete unit made of comparatively few parts, easy to assemble and certain in operation; capable of being produced without entailing great expense, and relatively small in size, so that it can be readily installed at the place of operation.

Another object is to provide a liquid mixing and dispensing unit which is controlled in the usual way when a coin is deposited to drop a cup into position and to set into motion the parts by which the drink is mixed and poured into the cup; but which has a compact arrangement of pipes through which the liquid is conducted and a superior mode of operation by means of valves and actuating members on the outside of the apparatus and in readily accessible position.

The nature and advantages of my invention are made clear in the following description, taken with the drawings, showing an embodiment of my invention in practical form. This disclosure, however, is explanatory only, and many variations in detail may be adopted without deviation from the general plan that distinguishes the invention.

On the drawings:

Figure 1 is a top view of a beverage vending apparatus according to my invention.

Figure 2 is a front elevation thereof in position to deliver its contents, behind a panel or partition screening the apparatus.

Figure 3 is a vertical section in the plane of the line 3—3 on Figure 1.

Figure 4 is a vertical section taken in the plane of the line 4—4 on Figure 3.

Figure 5 shows the dispensing member by which both the liquid and the flavoring syrup are forced into the mixing casing enclosing a mixed chamber.

Figure 6 is a vertical section through the mixing casing enclosing a mixing chamber.

Figure 7 is a top plan of the parts for controlling the flow of the liquids in their passage through the apparatus and their eventual expulsion therefrom.

Figure 8 is a transverse vertical section on line 8—8 on Figure 7.

Figure 9 is a top plan of the member in which the controlling valves are seated and upon which the operating parts are mounted.

Figure 10 is a perspective view of one of the valve members; and

2

Figure 11 is a section on the plane of the line 11—11 on Figure 10.

The numeral 1 indicates the main casing or housing of the apparatus and 2 a shelf, counter or other support for the housing or body 1. The casing or body 1 is equipped with legs 3. When installed in readiness for use, the apparatus will be behind a partition, panel or the like to screen it from view and only the drinking cup and the tap from which the ready mixed drink pours into the cup will be visible. Inside the housing is a container 4 full of carbonated water; and the container for the syrup is shown at 5. An ad-measured quantity of each is transmitted to a mixing cup 6 of inverted conical shape, in which the drink is thoroughly agitated; and from the bottom of the casing enclosing a mixing chamber 6 the potion is discharged through a conduit 7. Beside the housing 1 is a casing 8 containing stacks of paper cups or other drinking vessels in vertical tubular discharge chutes or magazines 9. The panel 10 screening the unit and the casing 8 may have window openings therein in front of the casing 8, so that the cups therein will always be in view and can be replenished when nearly exhausted. At the bottom of the magazine the panel has an opening or recess 11 at the level of the support 2, upon the bottom of which the cups are dropped, mouth up, one by one to be filled. The end of the pipe 7 is inclined downward and is disposed just far enough to one side to be cleared by each cup 12 as it is dropped from the magazine 8. Guides may be affixed to the inside of the recess 11 to prevent the cups from overturning.

The panel 10 bears a metal strip 13 containing a coin slot 14. The usual mechanism is utilized to respond to the insertion of a coin to set the apparatus into operation. Such mechanism includes an electric circuit and members actuated thereby to bring about the dropping of a cup into position as shown in Figure 2, and the actuation of the valves which open the passages through which the liquid and the syrup are conducted into the mixing cup and then delivered to the drinking cup 12. The design of such parts is well known and needs no full description here, except to say that the principal member for actuating the valves is an electromagnet 15 on the top of the housing 1, adjacent the rear face of the panel 10. This magnet acts when energized to pull back a spring-projected plunger armature 16, bearing a pawl 17 pivotally mounted on the outer end thereof. The hooked end of this pawl engages the teeth of a ratchet wheel 18, fixed to the outer end of an upright short shaft 19. This

shaft carries a gear 20 keyed thereto, and this gear 20 meshes with similar gears 21 and 22, one on each side thereof. The shaft 19 and the gears 20, 21 and 22 are mounted in a seating member or gear block 23 secured to the top of the housing 1 in front of the magnet 15. The member 23 has a central vertical bearing open at the upper end, for the shaft 19, and at each side of this bearing are upward extending bosses 25 and 26, open at the top, constituting valve casings for seating the valves by which the ducts leading from the reservoirs 4 and 5 to the mixing casing enclosing a mixing chamber 6 are controlled, as will be presently explained. The hub of the gear 20 rests on the top of the bearing 24, and between this gear 20 and the ratchet wheel 18 is a star or escapement wheel or disk 27, with concave recesses in its rim to be engaged by the convex end of a leaf spring 28, affixed to a post 29 on the casing 1 beside the magnet 15. As illustrated, whenever a coin is dropped and the circuit of the magnet 15 is closed, the ratchet wheel 18 is rotated through one quarter of a complete turn. A spring 30 on the plunger 16 holds the pawl 17 in engagement with the ratchet 18.

The container 4 is kept charged with carbonated liquid under pressure by connection with a supply pipe 31 that runs in through the wall of the housing 1 and is connected to a coil 32 that envelops the syrup container 5, which is at the center of the housing. The inner extremity of the coil 32 is coupled to the receptacle 4, as shown at 33. From the container 4 leads a conduit 34 to the end of the block 23 shown at the right upon Figure 8. Other pipes or conduits 35 and 36 respectively connect the same part of the block 23 to the lower end and upper end of a cylinder 37 in the housing 1, disposed between the coil 32 and the side of the housing adjacent the screen or panel 10. The cylinder 37 has nipples 35' and 36' by which the conduits 35 and 36 respectively can be conveniently coupled to the cylinder 37. At 38 is a delivery pipe leading from the block 23 adjacent the other pipes 34, 35 and 36 to the mixing casing enclosing a mixing chamber 6.

Similarly, from the tanks 5, which can be kept filled with syrup as indicated at 39, through the top of the housing 1, a conduit 40 leads from a point near the bottom of the container 6 to the block 23 at the opposite end of the latter. This part of the block 23 is coupled by pipes 41 and 42 respectively to the lower and upper ends of a smaller cylinder 43. The latter is on top of the cylinder 37, and has nipples 41' and 42' for the ready attachment of the conduits 41 and 42. Another conduit 44 associated with the conduits 40, 41 and 42 leads from the block 23 to the mixing casing enclosing a mixing chamber 6. The ends of the conduits 38 and 40 are coupled to nozzles 45 and 46 respectively, discharging into the vessel 6, the former above the latter and both turned so that they discharge towards each other, and thus ensure a full mixing effect. At the lower end of the casing enclosing a mixing chamber 6 is a nipple 47 coupled to the delivery pipe 7.

The upper or larger end of the casing enclosing a mixing chamber 6 is closed by a top 48 and is connected to the atmosphere by a vent pipe 49. The two cylinders 37 and 43 are connected by a coupling 50, and the cylinder 37 contains a piston 51. The upper or smaller cylinder 43 contains a piston 52. Both pistons are connected by a rod 53 that slides in the bearings in the coupling 50 and the adjacent end of the cylinder 37. The cylinders are measuring vessels and the two make

5 a single member to deliver measured quantities of the liquid and syrup.

The shaft 19 has a groove 54 and the bearing 24 a screw 55 to engage this groove and secure the shaft 19 against displacement. At each side of the bearing 24 is a rim or boss 56, these bosses encircling and housing the valves 25 and 26 therein. These valves have the form of circular disks, each with a transverse rib 57 across the top. Resting upon each valve is a head 58, each having a transverse groove 59 in its under side to receive the rib 57. The bosses are closed by caps 60 screwed into the upper ends; and these caps have central bearing apertures for the passage of shanks 61 integral with the heads 58. The shanks 61 have longitudinal threaded bores to receive screws 62 with round inner ends which bear down upon the ribs 57. The keys for the gears 20, 21 and 22 are shown at 63. The gears 21 and 22 rest on the caps 60 and the keys connect the gears to the shaft 19 and 61 so as to make the gears and the shafts turn together.

20 The inner ends or bottoms of the bosses 56 have depressions 64 in which are seated packing elements 65, and packing rings or gaskets 66 are disposed between the caps 60 and the heads 58 and between the caps and the edges of the bosses 56 to make the valves and the casings therefor leak-proof. The bottom of the block 23 and the packing disks 65 have registering apertures for attachment of the various pipes leading to the containers 4 and 5, the casing enclosing a mixing chamber 6 and the cylinders 37 and 43 respectively. These apertures on Figure 8 have numbers which are the same as the numbers of the respective pipes joined to apertures and in each instance the letter "a" is added. Each valve 25 and 26 has a pair of ports 67 at each side, the ports of each pair being united by straight ducts 68.

30 The pressure of the carbonated water in an outside reservoir connected to the coil 32 will cause the liquid to flow into the cylinder 37 and move the piston 51 up or down, according to which end of the cylinder receives the water. The movement of the piston 51 causes movement of the piston 52. When a coin is dropped into the slot 14, the magnet 15 turns the shaft 19 and both valves 25 and 26.

40 Suppose both cylinders are filled above the pistons and the latter are near the bottoms of the cylinders; as in Figure 5, and that the magnet causes the valve 25 to connect the two pipes 36 and 38, and 34 and 35. The pressure of the fluid below the piston 51 will force the piston 51 upward, discharging the contents of the cylinder through the pipes 36 and 38 into the casing enclosing a mixing chamber 6. At the same time the cylinder 37 will be filled from below through the pipes 34 and 35. Likewise, the cylinder 43 now being filled above the piston 52, the movement of the valve 26 will now connect the pipes 42 and 40 to the casing enclosing a mixing chamber 6; and the pipe 44 to the pipe 41 leading to the lower end of the cylinder 43. The cylinder 43 will then simultaneously discharge through the pipe 40 into the casing enclosing a mixing chamber 6, and the lower part of the cylinder 43 will simultaneously fill with syrup.

50 When the pistons reach the upper limits of their movements, they remain stationary till another coin is inserted and then they are forced down. The valves are now shifted through 90 degrees, and the upper ends of the cylinders are joined to the containers 4 and 5 through the pipes

34 and 36, 44 and 42 respectively. The pistons are thus forced down and discharged again into the cup 6 by way of the pipes 35 and 38, 41 and 40 respectively. A ready mixed drink is thus always dispensed at the cavity 11.

The housing 1 has a cover 69 hinged at the top and having a knob 70 for raising it. The tank 6 is encircled by a cooling coil 71 having an inlet 72 and an outlet 73 and supporting legs 74, and the tank 6 is supported on legs 75 in the housing 1. The member 23 is affixed to the top of the housing by screws for which holes 76 are provided in this member. The tank 5 is adapted to receive a liquid refrigerating medium which is kept at a low temperature by the contents of the cooling coil 71.

The construction of the apparatus is thus comparatively simple, comprising few parts that are easy to produce and assemble. The apparatus can be built at a reasonable cost and is certain in operation and durable in construction.

The upper end of the cylinder 43 is closed by a screw cap 77, with a bearing aperture 78 therein. This aperture or port is intended to allow the insertion of a rod indicated at 79 which can be screwed into a threaded hole 80 in the piston 52. This rod is utilized occasionally for testing the pistons 51 and 52 and working them free. When the rod 79 is not needed the port 78 is closed by a cap 81 screwed upon the boss 82 surrounding the port 78.

The housing 1 is flat on the side adjacent the panel and rounded on the opposite side, and the lid 69 has approximately the shape of a half-circle. The tank 5 is preferably round and is disposed mostly under the cover 69 and adjacent the rounded side of the housing, to make room for mixing cup 6 and the cylinders 37 and 43 near the flat side of the housing; the container 4 being under the container 5.

Having described my invention, what I believe to be new is:

1. Apparatus of the kind described comprising a housing, a container for a liquid under pressure, a separate container for a flavoring substance, a mixing casing and a pair of measuring vessels each enclosing a movable part, all in said housing, pipe connections from one of said vessels to the container for liquid and the mixing casing for delivering a quantity of said liquid to the mixing casing, pipe connections from the other of said vessels to the other container and the mixing casing for delivering a quantity of said flavoring substance to the mixing casing, and means for controlling all of said connections, said casing having an outlet at one end, a nozzle in the casing adjacent the outlet coupled to the connections for the flavoring substance, and another nozzle in said casing adjacent the other end thereof coupled to the connections for said liquid, said nozzles being mounted to discharge towards each other in the casing to diffuse the flavoring substance in the liquid before discharge through said outlet.

2. Apparatus of the kind described comprising a housing, a container for a liquid under pressure, a separate container for a flavoring substance, a mixing casing and a pair of measuring vessels each enclosing a movable part, all in said housing, pipe connections from one of said vessels to the container for liquid and the mixing casing for delivering a quantity of said liquid to the mixing casing, pipe connections from the other of said vessels to the other container and the mixing casing for delivering a quantity of said

flavoring substance to the mixing casing, and means for controlling all of said connections, said mixing casing having an outlet at one end, a nozzle in said casing adjacent the outlet, coupled to the connections for the flavoring substance, and another nozzle in said casing adjacent the other end thereof coupled to the connections for said liquid, said nozzles being mounted to discharge towards each other in the casing to diffuse the flavoring substance in the liquid, said controlling means comprising a pair of valves on the exterior of the housing, one of said valves being disposed in the connections between the container for the flavoring substance and said casing, and the other of said valves being disposed in the connections for the container for liquid and said casing, said valves being connected to be operated in unison, and means for actuating said valves.

3. Apparatus of the kind described comprising a housing, a container for liquid under pressure, a separate container for a flavoring substance, a pair of measuring vessels each containing a movable part, and a mixing chamber, all in said housing, connections between one of said vessels and the container for liquid and said casing for delivering a quantity of said liquid to said casing, connections between the other vessel, the other container and said casing for delivering a quantity of flavoring substance to said casing, which has the form of an inverted cone in said housing with a delivery outlet at its smaller end, a nozzle in the casing adjacent the smaller end coupled to the connections for the flavoring substance, another nozzle in the casing adjacent the opposite end thereof coupled to the connections for the liquid, a cooling coil in the housing surrounding the container for the flavoring substance, said casing and said vessels, a discharge pipe leading to the exterior of the housing from the outlet of the casing, the other end of said casing having a cover with an opening therein and an air pipe connecting said opening to the outside of the housing, and means for controlling all said connections, said nozzles being mounted to discharge towards each other in the casing to diffuse the flavoring substance in the liquid before discharge from the casing.

4. Apparatus of the kind described comprising a housing, a container for liquid, a separate container for a flavoring substance, a mixing casing and a pair of measuring vessels each enclosing a movable part, connections between one of said vessels and said casing and the container for flavoring substance, connections between the other of said vessels and the casing and the container for liquid, means for controlling said connections comprising a pair of valves, a block on the exterior of the housing having seats for the valves, the block also having a bearing open at its outer end only, a shaft in the bearing having one end projecting therefrom, gearing connecting the shaft to said valves and means for operating the shaft to actuate said valves.

5. Apparatus of the kind described comprising a housing, a container for liquid and a separate container for a flavoring substance, a mixing casing and a pair of measuring vessels each enclosing a movable part, connections between one of said vessels and said casing and the container for flavoring substance, connections between the other of said vessels and the casing and the container for liquid, means for controlling said connections comprising a pair of valves, a block on the exterior of the housing having seats for the

valves and the block also having a bearing open at its outer end only, a shaft in the bearing having one end projecting therefrom, gearing connecting the shaft to said valves and means for operating the shaft to actuate said valves, said means comprising a ratchet on the shaft and a pawl to turn said ratchet.
